LAMP BASE

Henry O. Strehl, 3920 E. Washington,
Phoenix, Ariz. 85034

Filed June 18, 1968, Ser. No. 12,410

Term of patent 14 years

Int. Cl. D26—02

U.S. Cl. D48—20

FIG. 1

FIG. 2

FIG. 3

FIG. 1 is a front elevation of the lamp base.
FIG. 2 is a left hand side elevation of the lamp base.
FIG. 3 is a right hand side elevation of the lamp base.
FIG. 4 is a top view of the lamp base.

The lamp shade is shown in broken lines in FIG. 1 for illustrative purposes only.

I claim:

The ornamental design for a lamp base, as shown and described.
